UNITED STATES PATENT OFFICE.

JOHN H. SCHUSSLER, OF CHICAGO, ILLINOIS, ASSIGNOR TO ACME PRINTING APPLIANCE COMPANY, OF CHICAGO, ILLINOIS, A CORPORATION OF ILLINOIS.

ELECTRICALLY-HEATED EMBOSSED-BASE.

1,217,226.

Specification of Letters Patent. Patented Feb. 27, 1917.

Application filed February 15, 1915. Serial No. 8,307.

To all whom it may concern:

Be it known that I, JOHN H. SCHUSSLER, a citizen of the United States, residing at Chicago, in the county of Cook and State 5 of Illinois, have invented certain new and useful Improvements in Electrically-Heated Embossing-Bases, of which the following is a specification.

This invention relates to electrically heated embossing bases or plates, and it has for its principal object to provide means whereby an improved grade of embossing may be done in an ordinary printing press. Owing to the fact that satisfactory embossing can 10 be done only by means of a hot embossing plate it has been impossible to do good work on an ordinary printing press as there has been no means for heating the embossing plate and die. My invention provides an 15 electrically heated embossing plate upon which any desired embossing die may be secured, and which may be secured to the bed of an ordinary printing press. My improved 20 embossing base or plate may be employed 25 with either a platen press or with a cylinder press. A further feature of my invention is the provision of means for varying the temperature of the embossing plate, as desired. Another important feature of my invention 30 is the provision of improved means for securing the embossing die to the embossing base or plate. Still another object of my invention is to provide an improved embossing base of the kind above referred to which 35 may be secured in the chase of a cylinder press, or a platen press. A further important object of my invention is to provide a device of this character in which the embossing die will be held in a position corresponding 40 to the height of ordinary type in the press, regardless of the thickness of the die, and in which the heat will be largely kept away from the bed of the press against 45 which the die-holding and heating device may be secured; and I also provide improved means for ventilating the bed of the press.

These and other features of my invention 50 will be more particularly set forth in the following specification taken in connection with the accompanying drawings in which I have illustrated a specific embodiment of my invention.

55 Referring to the drawings,—

Figure 1 shows a top plan view of my im-

proved embossing base or plate secured in position on the bed of a printing press and having two embossing dies secured to the upper side thereof;

Fig. 2 shows a bottom plan view of the 60 embossing base illustrated in Fig. 1, the bottom cover-plate and the insulation being removed and certain details being shown in section;

Fig. 3 shows a diagrammatic top plan 65 view of my improved embossing base secured in position within the chase of a printing press;

Fig. 4 shows an enlarged sectional view taken along the line 4—4 of Fig. 1;

Fig. 5 shows an enlarged detail sectional view taken along the line 5—5 of Fig. 1;

Fig. 6 shows an enlarged sectional view taken along the line 6—6 of Fig. 1;

Fig. 7 is an enlarged sectional detail view 75 taken along the line 7—7 of Fig. 1;

Fig. 8 shows a perspective view of the locking key or wrench; and

Fig. 9 shows a perspective view of a locking plate for use in securing the die on the 80 base.

Referring to the drawings, the bed of an ordinary printing press, designated generally by the numeral 10, is shown as comprising the parallel guides or end walls 11, at 85 the opposite ends thereof, and a locking lever 12 pivotally mounted at the forward side thereof. My improved embossing base, designated generally by the numeral 13, is adapted to be detachably secured to the bed 90 10 and comprises a base plate or frame member 14 having the interior chamber 15 which is normally closed by the bottom cover-plate 16. The cover-plate 16 is secured to the base-plate or frame member 14 by means of 95 screws 17 engaging threaded apertures 18 which are provided in the under-side of said frame member.

At each of its rear corners the frame member or base plate 14 is provided with an integral projection 19 which extends outwardly from said frame member along each lateral edge thereof, adjacent the corner, the portions 19^a of said lugs along the ends of the base-plate being adapted to coact with 105 the guides or end walls 11 of the bed 10, and serving to space the base-plate therefrom, while the portions 19^b of the lugs which extend along the rear side of the base-plate have their upper surfaces tapered or curved 110

downwardly, as shown in Fig. 7, and are adapted to coact with the integral lugs 20 formed on the walls 11 for the purpose of retaining the base-plate in position on the bed of the press. The lugs 20 which extend inwardly from the walls 11 overlap the portions 19^b of the integral lugs 19 and are provided with surfaces 20^a which coact with the edges of the lugs 19, when the base-plate is in position on the press. The base-plate is maintained in such position with the lugs 19 coacting with the integral projections 20 by means of the locking lever 12, which is provided with an inwardly extending hooked projection 12^a adapted to extend over an integral projection 21, which is formed on the base-plate 14 on the opposite side from the lugs 19. The upper surface of the integral projection 21 is curved downwardly, as shown in Fig. 7, similar to the upper surfaces of the portions 19^b of the lugs 19, and the projection 21, as well as the portions 19^b, are made considerably longer than is necessary for the purpose of locking the base-plate on the bed of the press shown in the drawings, in order that my improved base-plate may be employed in connection with presses in which the locking means corresponding to the lugs 20 and lever 12 are differently located. Adjacent the forward corners of the base-plate are integral projections 22 similar to the portions 19^a of the lugs 19 and similarly located at the ends of the base-plate in order to space said plate from the guides or walls 11. It will be seen that the portions 19^a and the projections 22 serve to provide air spaces 23 at each end of the base plate for a purpose to be herein-after described.

Extending downwardly into the chamber 15 of the base-plate or frame member 14 are a plurality of parallel elongated lugs or projections 24, shown particularly in Figs. 2 and 4, which lugs are preferably rectangular in shape and arranged to coact with the cover-plate 16 which is secured thereto in the manner previously described. These lugs or projections 24, and also the lateral walls of the chamber 15, are provided on their lower surfaces with a plurality of integral circular projections 25 which extend downwardly through corresponding circular apertures 26 in the cover-plate 16 and some distance beyond said plate, being provided at their lower ends with plane surfaces which coact with the upper surface of the bed 10 of the press. It will be seen that the lugs 24 and projections 25 serve to firmly support the upper wall of the base-plate above the chamber 15 so as to transmit any pressure exerted upon the upper surface of said base-plate to the bed of the press, and at the same time the lugs 25 projecting downwardly beyond the lower cover-plate 16 serve to provide an air space 26 which underlies the en-

tire base-plate between the lugs 25, and which communicates with the air spaces 23, above mentioned, at the ends of the base-plate so that a continuous circulation of air is provided beneath the base-plate and the parts carried thereby.

Upon referring to the drawings, it will be seen that the downwardly projecting rectangular lugs 24 serve to divide the chamber 15 of the base plate into a plurality of parallel grooves or chambers 27 which communicate with similar grooves or chambers 28 which extend along the edges of the base-plate at the ends of the lugs 24. In order to provide the chambers 27 of suitable dimensions for a purpose to be hereinafter described, and in order to add strength to the structure while permitting a relative thinness of metal at the points 29, I provide the walls of the chambers 27 and 28 substantially semi-circular in contour, as shown particularly in Figs. 4 and 6. This formation adds great strength to the structure and serves to transmit to the lugs 24 the pressure which is received by the base-plate above the chambers 27 and 28.

The chambers 27 and 28, generally referred to as the chamber 15, are filled with porcelain, or other suitable insulating material which has embedded therein a plurality of interconnected electrical heating coils by means of which I heat the embossing base and the parts carried thereby. These coils are arranged parallel to each other in the chambers 27, and are interconnected by means of electrical conductors extending through the chambers 28. In order to provide means for heating the embossing base to different degrees of heat, as desired, I have arranged these coils in a plurality of circuits which may be connected in parallel to vary the number of coils which are in the operative circuit at any time. Referring to Fig. 2 of the drawings, it will be seen that the coils 30, 31, 32, 33, 34 and 35 are connected in series to form one of the parallel circuits above mentioned; that the coils 36, 37, 38, 39 and 40 are connected in a series to form another of said parallel circuits; and that the coils 41, 42, 43, 44 and 45 are connected in series to form the third of said parallel circuits. One extremity of each of the above-mentioned parallel circuits is connected adjacent the proper extremities of the coils 30, 36 and 41, respectively, to a terminal 46, and the other extremity of the first mentioned circuit is connected from the coil 35 to another terminal 47, and the supply of electric current is supplied to the circuits through these terminals. The first-mentioned circuit is connected between the coils 32 and 33 to the common posts 48^a of a three-post switch 48 by means of which the second and third parallel circuits are connected in parallel

with portions of the first-mentioned circuit. The terminal of the second-mentioned circuit, opposite the terminal 47, is connected directly from the end of the coil 40 to the 5 intermediate split-post 48^b of the switch 48 and the terminal of the coil 45 of the third-mentioned circuit is connected directly to the third split-post 48^c of the switch 48. The intermediate post 48^b of the switch 48 is 10 made considerably longer than the post 48^c, so that when the blade or knife 48^d of said switch is partially closed it will contact with the post 48^b and thereby connect the second-mentioned circuit in parallel with a 15 portion of the first-mentioned circuit without contacting with the third post 48^c of the switch, thus leaving the third-mentioned circuit disconnected from the operative circuit, as shown in Fig. 2 of the drawings. 20 When the knife 48^d of the switch is completely closed it will form a connection with the third post 48^c, and thereby connect the third-mentioned circuit in parallel with each of the other two circuits. In this way 25 three degrees of heat are provided so that the degree of heating of the embossing base and die carried thereby may be regulated, as desired.

The supply terminals 46 and 47 each comprises a socket member 49, having an inwardly extending projection to which the proper conductors within the embossing base are electrically connected, and this socket is carried in insulated condition in a chamber 30 formed in the insulating block 50 which is provided with two cylindrical portions 51 which extend into corresponding apertures in the wall of the embossing base so as to completely insulate the socket members 49 35 from the metal of the base-plate. The insulating block 50 is secured to the base-plate by screws or other suitable means, and the apertures in the socket members 49 are adapted to be engaged by split plugs 52 of 40 conducting material which are carried by a portable insulating block 53, and which are electrically connected to the conductors 54 of the supply circuit. By this construction a convenient means is provided for making 45 the connection to the circuits within the embossing base-plate after said base-plate has been assembled on the bed of the press. Each of the split-posts of the switch 48 is cylindrical in form and provided with an annular 50 shoulder 55, which shoulder seats upon an insulating block 56 which the split-post 55 threadedly engages and which is attached to the base-plate by screws or similar means. The lower portion of each post extends 55 through the block 56 in alinement with the central aperture of an insulating bushing 57. Each switch-post is further provided with a central aperture which receives a pin 58 of 60 conducting material and each of these pins is secured in position by means of the set

screws 59. The pins 58 extend inwardly into the chamber of the base-plate and have connected thereto the proper parts of the parallel circuits above mentioned.

In order that my improved embossing 70 base may be used in any ordinary printing press in such manner that the embossing die carried thereby may be held at the height with respect to the bed of the press normally occupied by the usual printing 75 type, I employ spacing plates 60 for the purpose of spacing the dies 61 and 62 from the upper surface of the base-plate proper. The spacing plate 60 is secured to the base-plate by means of screws 63 and is provided with a plurality of apertures 64 extending therethrough and arranged in rows longitudinally and transversely of the said 80 spacing plate, as shown particularly in Fig. 1. These apertures are countersunk or beveled outwardly at their upper extremities 85 so that the heads of screws passing through said apertures will so far as is necessary engage the holes in said plate, and said apertures are further arranged to align with 90 the rectangular projections 24, which extend downwardly in the chamber 15 of the base-plate, in order that said apertures 64 may register with threaded apertures 65, which extend downwardly into the projections 95 44 and also into the walls of the chamber 15 around the borders of the base-plate.

The purpose of a plurality of apertures 64 and 65 is to permit of the attachment to the spacing plate and base-plate of embossing dies of varying size. This attachment is accomplished by means of a locking plate 66, (see Fig. 9), the outer contour of which is hexagonal in form and beveled from each face of the plate so as to provide a sharp 100 projecting edge 67, which is adapted to bite into the edge of the embossing die when said locking plate is secured in position adjacent thereto, as shown particularly in Fig. 5. The locking plate 66 is provided 105 with a circular aperture 68 which is non-symmetrically located with respect to the lateral edges 66^a of said plate so as to be spaced a different distance from each one 110 of said lateral edges. Extending around 115 the lower portion of the aperture 68 is an annular shoulder 68^a, which forms a seat for a locking disk 69, the upper surface of which lies flush with the upper surface of the plate 66, and which is provided with 120 an eccentrically located aperture 70 of suitable form to be engaged by a screw 71. The screw 71 extends through one of the apertures 65 in the spacing plate and engages one of the threaded apertures 65 in the base 125 plate. The eccentric locking disk 69 is further provided with a rectangular or other suitable aperture 72, which is adapted to be engaged by a wrench 73 having an extremity 73^a of the same contour as said 130

aperture. By means of the construction above described, it will be seen that a very large variation in adjustment may be secured so as to secure a tight engagement 5 between the locking plate 66 and the adjacent edge of the die which is to be secured upon the embossing base.

After selecting a suitable aperture 64 adjacent the edge of the die to be secured on 10 the base, the non-symmetrical location of the aperture 68 in the plate 66 will permit six different degrees of adjustment by rotating the plate 66 so as to bring the proper edge 66^a thereof into approximate engagement with the adjacent edge of the die.

After this portion of the adjustment has been made the wrench 73 may be operated to rotate the eccentric disk 69 about the screw 71 until the edge of the plate 66 bites 20 into or very tightly engages the edge of the die, after which the screw 71 is rotated to tightly clamp the parts of the locking mechanism to the spacing plate and base plate. Referring to Fig. 5, it will be seen 25 that the annular shoulder 68^a spaces the disk 69 from the upper surface of the spacing plate 60, so that the downward pressure of the head of the screw upon the locking disk operates to exert a very effective 30 clamping pressure upon the locking plate 66. In order to lock the die securely upon the base it is necessary to use a plurality of locking devices, above described, as shown in Fig. 1 of the drawings, and if 35 desired, various forms of these locking devices may be employed; for instance, instead of using a locking plate having a hexagonal contour, I may use one which is rectangular in form, as shown for instance 40 at 74, having an aperture therethrough corresponding to the aperture 68 in the plate 66, this aperture being symmetrically located with respect to the lateral edges of the plate 74, although it may be non- 45 symmetrically located, if desired. Another form of locking device, shown in Fig. 1, comprises a rectangular plate 75 which is provided with a non-symmetrically located aperture adapted to be directly engaged by 50 a screw 76.

I have also shown another form of locking device in which the plate 66^b is circular in form, being provided with a non-symmetrically located circular aperture in 55 all respects similar to the aperture 68 above described, which is adapted to be engaged by the disk 49, which in this case is centrally apertured. The key-way 72^a in this form is provided in the plate 66^b. It will 60 be apparent that an exceedingly large range of adjustability may be had when this locking device is employed.

Where it is desired to emboss two designs 65 printed upon the same sheet, I may employ the two dies 61 and 62, for instance, and

after first locking one of the dies 61 in position, by means of the locking devices, so as to register with the print to be embossed by said die, the other die 62 is adjusted by means of the adjustable locking device 70 above described until said die registers with the other print to be embossed upon the same sheet. The first die 61 to be secured in position may be locked by means of the plates 75, which permit a somewhat limited 75 degree of adjustability, and the plates 66 and 74, which permit a relatively large degree of adjustability, may then be used for moving the other die 62 into proper register with the print to be embossed.

I have also provided a scoring rule 77, which has two or more slots 78 extending transversely thereof, and which is adapted to be secured to the embossing base by screws 79 engaging said slots and entering 85 suitably located ones of the holes 64 and 65, above described. The up-turned edge 77^a of the scoring rule is adapted to coact with a complementary member carried by another part of the press in such manner as 90 to introduce a "crimp" or "fold line" in the paper or fabric being embossed. It will be evident that the adjustability permitted by the slots 78 and the plurality of holes 64 and 65 will enable the operator to form the 95 "fold lines" in any desired location. The edge 77^a of the scoring rule 77 should preferably terminate at substantially the same height as the top surfaces, embossing dies being used.

In some instances it may be desirable to use my improved embossing base in connection with the chase of a printing press, such as a cylinder press, and in Fig. 3 of the drawings I have shown a chase 80 provided with the usual lateral walls or shoulders 81 and having my improved embossing base 13^a secured therein by the usual "printers' furniture" 82. As is well known, this "furniture" comprises a plurality of adjustable blocks or other means for tightly clamping the base in the chase, and I have merely shown one representation thereof for the purpose of illustrating this adaptation of my embossing base, and for the purpose of showing that the embossing base 105 may be secured in a chase by this means without the "furniture" or other adjusting means interfering with the switch 48 or the integral projections 19, 21, and 22 of the 110 embossing base.

From the foregoing description it will be seen that my improved embossing base may be conveniently and adjustably secured on the bed of an ordinary printing press and in such manner as to provide a free circulation of air around and beneath the base so as to prevent the undue heating of the bed of the press and the lower part of the embossing base. At the same time my im- 115 120 125 130

proved electrical heating means permits of a very effective heating of the upper part of the embossing base and the embossing dies carried thereby so that a very high 5 grade of embossing may be done. The use of the spacing plate 60 permits the location of the die in such manner that the upper part of the die will occupy the position normally occupied by the upper parts of the 10 usual printing dies, and it will be understood that while I have shown a particular thickness of base plate, various thicknesses of plates may be used to correspond with the thickness of the die which is being employed 15 in the particular embossing operation. In order to provide the wide range of adjustability with respect to the mounting of the dies, it is necessary to limit the height of the base plate 14, and it will be seen that 20 the substantially semi-circular contour of the chambers 15 permits a relative thinness of the metal at the points 29 so as to transmit the pressure to the longitudinal projections 24 and thereby decrease the necessary 25 height of the base plate 14 without detracting from the strength thereof. It will be seen that the thinness of metal at the points 29 also permits the heat generated in the electrical heating coils to be readily transmitted 30 upwardly through the spacing plate to the embossing die or dies to be heated. Another important advantage of the invention lies in the improved means which I have provided for heating the embossing base to 35 various different degrees of heat by connecting in the operative circuit a varying number of heating coils.

While I have illustrated a specific embodiment of my invention and have described the same as being employed in a particular manner, it will be understood that my invention may be modified in form and arrangement of parts, and that it may be adapted to different uses without departing 45 from the spirit thereof, as defined in the appended claims.

What I claim is:—

1. In an electrically heated embossing device, a base plate having a chamber, insulating material in said chamber, and an electrical heating member embedded in said insulating material.
2. In an electrically heated embossing device, a base plate having a chamber, a plurality of electrical heating members spaced apart and held in insulated condition in said chamber, and a switch included in an electrical circuit with said heating members and arranged to vary the number of heating members in operation, said switch and circuit being arranged to provide uniform heating of said embossing device when a part of the heating members only are in operation.
3. The combination in an electrically heat-

ed embossing device of a base plate having a chamber, a plurality of interconnected electrical heating coils held in insulated condition in said chamber, and a switch in circuit with said heating coils, said switch being arranged to vary the number of said coils in an operative circuit. 70

4. In an electrically heated embossing device, a base plate having a chamber, an electrical conductor held in an insulated condition in said chamber, a cover for said chamber, and lugs in said chamber formed integrally with said base plate for transmitting pressure through said plate. 75

5. In an electrically heated embossing device, a base plate having a chamber, an electrical conductor held in an insulated condition in said chamber, a cover for said chamber, and rectangular lugs formed integrally with said base plate and extending downwardly into said chamber for transmitting pressure through said plate, the spaces between said lugs being substantially semi-circular in cross section. 80

6. In an electrically heated embossing device, a base plate having a chamber, an electrical conductor held in an insulated condition in said chamber, a cover for said chamber, and lugs formed integrally with said base plate and adapted to be engaged by holding devices carried by a printing press. 90

7. In an electrically heated embossing device, a base plate having a chamber, an electrical conductor held in an insulated condition in said chamber, a cover for said chamber, lugs formed integrally with said base plate and adapted to be engaged by holding devices carried by a printing press, and other lugs formed integrally with said base plate for spacing said plate from the walls of the press. 100

8. In an electrically heated embossing device, a base plate having a chamber, an electrical conductor held in an insulated condition in said chamber, a cover for said chamber, lugs in said chamber formed integrally with said base plate for transmitting pressure through said plate, and spacing lugs formed integrally with said first named lugs and projecting through said cover for spacing said base plate from the bed of the printing press in which it is secured. 110

9. In an electrically heated embossing device, a base plate having a chamber, an electrical conductor in said chamber, a cover for said chamber, lugs in said chamber for transmitting pressure through said plate, and insulating material in said chamber in which said electrical conductor is embedded. 120

10. In an electrically heated embossing device, a base plate having a chamber, elongated bars formed integrally with said base and extending into said chamber to transmit pressure therethrough, the spaces between said bars being substantially semicircular in 130

cross section, insulating material in said spaces, heating coils embedded in the insulating material, a cover for said chamber, and an electrical circuit for varying the 5 number of heating coils in operation.

11. In an electrically heated embossing device, a base plate having a chamber, a plurality of pressure-transmitting members formed integral with said base plate and extending into said chamber, insulating material in said chamber between said members, heating coils embedded in said insulating material in the spaces between said members, electrical conductors embedded in said

insulating material at the ends of said members for connecting the heating coils, and a switch mounted on said base plate for varying the number of heating coils in operation, said coils being connected to provide a uniform heating of said base plate when a 15 part only of the coils are in operation.

In testimony whereof, I have subscribed my name.

JOHN H. SCHUSSLER.
